UNITED STATES PATENT OFFICE.

JOEL MILLER, OF PHILADELPHIA, PENNSYLVANIA.

HORSE-BOOT.

SPECIFICATION forming part of Letters Patent No. 288,836, dated November 20, 1882.

Application filed September 3, 1883. (No model.)

To all whom it may concern:

Be it known that I, JOEL MILLER, a citizen of the United States, residing in Philadelphia, Pennsylvania, have invented certain Improvements in Horse-Boots, of which the following 5 is a specification.

The object of my invention is to construct a horse-boot which will be strong and durable, and which will readily adapt itself to the size 10 of the hoof, and can be firmly retained thereon. This object I attain in the manner hereinafter set forth, reference being had to the accompanying drawings, in which—

Figure 1 is a side view of my improved horse-boot; Fig. 2, a rear view of the same; Fig. 3, 15 detached perspective views of part of the boot, and Fig. 4 a sectional view of the toe-joint.

The boot comprises the toe-piece A, side bars, B B, and straps D, E, F, G, and H. 20 The toe-piece consists of a base-plate, a, forming the toe-calk of the boot, and having lugs b b, a tongue, d, and a central opening, f.

The front end of each side bar, B, has a recess, g, and projection h, with opening i, the 25 projection of one bar being adapted to the recess of the other, and a pin, J, being adapted to the openings i of the bars and to the opening f of the toe-piece, and then riveted so as to pivot the side bars together and to the toe-piece, thereby permitting the expansion and 30 contraction of said bars to suit hoofs of different sizes. The ends of the bars form a snugly-fitting rule-joint, so that strain and wear due to loose fitting at this point are avoided, and 35 the lugs b serve to protect the joint from blows which would loosen or impair the same.

The tongue d serves as a means of securing the front strap, D, which is held by a rivet, j, and to said strap D is riveted the lower binding-strap, E, which passes through eyes m on 40 lugs n on the side bars, B, and has its rear ends connected by a suitable buckle.

The fetlock-strap F is riveted to the strap E

near the front of the latter, and passes through one of the looped straps G at the rear of the 45 boot, the ends of the strap F being also secured by a buckle.

There are in the present instance two looped straps G, one higher than the other, the object 50 of this being to permit the adjustment of the strap F as the size of the hoof may demand. More than two straps G may be used, if desired.

H is the front supporting-strap, which passes over the top of the hoof, and is riveted to the straps D, E, and F, so as to cause them to preserve their proper relation to each other. This 55 arrangement of straps provides for the secure confinement of the boot to the hoof, and yet permits the ready application or removal of the same, only two straps, E and F, having to be 60 manipulated.

The bars B B are furnished with the usual side calks, w. The straps D, E, F, G, and H are made of leather, that composing the strap D being stiff and heavy, so that it will retain 65 its proper position even when the boot is removed from the hoof.

I claim as my invention—

1. The combination of the jointed bars B and the pin J with the toe-piece having lugs b b, as set forth.

2. The combination of the pivoted side bars, the toe-piece having a tongue, d, the front strap, D, lower retaining-strap, E, fetlock-strap F, and supporting-strap H, as set forth.

3. The combination of the fetlock-strap F with a series of looped rear straps, G, of different heights, as set forth.

In testimony whereof I have signed my name to this specification in the presence of two sub- 80 scribing witnesses.

JOEL MILLER.
